UNITED STATES PATENT OFFICE.

CHARLES H. LAUFKOTTER, OF SACRAMENTO, CALIFORNIA.

BOTTLE-COOLER.

SPECIFICATION forming part of Letters Patent No. 251,902, dated January 3, 1882.

Application filed August 31, 1881. (No model.)

To all whom it may concern:

Be it known that I, CHARLES H. LAUFKOTTER, a citizen of the United States, resident at Sacramento, in the county of Sacramento and State of California, have invented a new and valuable Improvement in Bottle-Coolers; and I do hereby declare that the following is a full, clear, and exact description of the construction and operation of the same, reference 5 being had to the annexed drawings, making a part of this specification, and to the letters and figures of reference marked thereon.

Figure 1 of the drawings is a representation of a vertical longitudinal section. Fig. 2 is a vertical cross-section. Fig. 3 is a cross-section, 15 and Fig. 4 is a plan view.

This invention has relation to bottle-coolers; and it consists in the novel construction and arrangement of the ice-receptacle, water-chamber, bottle-tubes, and a cooling storage-chamber or refrigerator, as will be hereinafter 20 fully described, and particularly pointed out in the claim.

Referring by letter to the accompanying 25 drawings, A designates the case of the cooler, which has double walls B and C, the intervening space between said inner and outer walls being packed with any suitable non-conducting material, except at a point immediately in the rear of the ice-chamber D, where 30 a flue, E, connecting the ice-chamber D and the cooling-chamber F, which comprises the lower half of the case A, is located, to convey cold air from the ice-chamber to the cooling-chamber.

The ice-chamber D has a drip-pipe, G, leading from its bottom down through the cooling-chamber, to convey the waste water as the ice melts to a suitable receptacle beneath the 40 case A.

In front of the ice-receptacle is located the water-chamber H, having a faucet, I, through which drinking-water may be drawn. In restaurants this is an advantage, as it dispenses 45 with the use of the customary pitcher and affords a great saving of ice.

Both the ice-chamber and the water-chamber have covers provided with double walls and a packing of non-conducting material.

50 The edges of the ice chamber and of the water-chamber project above the top of the case A, the edge of the ice-chamber being slightly higher than that of the water-chamber, in order that the flanges of their respective covers

may not interfere with each other in displacing or replacing either of them.

At each end of the ice and water chambers, and a short distance therefrom, are arranged a series of bottle-tubes, J, of different sizes to suit the bottle to be placed therein for cooling. These bottle-tubes are secured in the top of the case A, their upper edges protruding slightly through top of the case.

The lower ends of the tubes J terminate some distance above the top of the cooling-chamber.

The walls C of the case are lined with zinc, as are also the bottoms and sides of the cooling and the tube-holding chambers. The top wall of the case A is of sheet metal.

The cooling-chamber is intended for the reception of reserve bottles, meats, cheese, and the like.

The bottle-tubes are filled and the bottles kept cool. As soon as they have been emptied of their contents the reserve bottles in the cooling-chamber are resorted to, to keep the bottle-tubes filled.

When ice is needed for making mixed beverages the lid of the ice-chamber may be removed and the ice obtained therefrom, the water required for mixing said beverages being drawn through the faucet from the water-chamber in a cold condition. The cold air descending from the ice-chamber to the cooling-chamber will of itself reduce the contents of the cooling-chamber to a low degree of temperature. The temperature is also quite uniform, especially if the ice-chamber be kept filled to an even degree.

This makes a very convenient bottle-holder for restaurants and saloons, but is equally susceptible of household use.

Having thus fully described my invention, what I claim as new, and desire to secure by Letters Patent, is—

In a bottle-cooler, the combination, with the ice-chamber D, water-chamber H, and cooling-chamber F, of the bottle-tubes J, secured in the top of the case A, and having their lower ends terminating above the top of the cooling-chamber, substantially as specified.

In testimony that I claim the above I have hereunto subscribed my name in the presence of two witnesses.

Witnesses: CHARLES H. LAUFKOTTER,
ALBERT C. TUFTS,
FRED. L. GEORGE.
